SEAL

George G. Canter, New York, N. Y.

Application November 17, 1948, Serial No. 60,603

8 Claims. (Cl. 292—317)

1

This invention relates to seals, more particularly to strap seals of the type suitable for use on freight cars, trucks and containers of various kinds for the shipment of valuable goods, the seal being removable only by destruction.

The objects of the present invention are to provide a seal of the type described which is inexpensive to manufacture, effective and positive in operation, incapable of being opened without showing obvious signs of tampering, and not likely to be rendered inoperative by careless handling.

The invention will best be understood by the following description of the present preferred embodiment thereof taken in conjunction with the drawings in which:

Fig. 1 is a plan view of a complete seal as supplied to the user;

Fig. 2 shows the seal in use on a common type of freight car lock;

Fig. 3 is a perspective view showing the disk and the associated, eventually enclosed end of the strap before these parts have been fastened together;

Fig. 4 is a view similar to Fig. 3 showing the same parts in their fastened relationship;

Fig. 5 is an enlarged sectional view showing the relative positions of the strap ends and disk at the moment when the free end of the strap first engages the tongue of the enclosed end;

Fig. 6 is a central sectional view through the completed seal showing the position of the parts when the free end of the strap has first been fully inserted in the enclosure;

Fig. 7 is a similar view showing the position of the parts when the free end of the strap has been pulled downwardly into engagement with the tongue on the enclosed end;

Fig. 8 is a similar view showing the position of the parts when a strong force has been applied in a direction tending to pull out the free end;

Fig. 9 is a plan view, partly in section, taken on the line 9—9 of Fig. 8;

Fig. 10 is a perspective view of the free end of the strap; and

Fig. 11 is an enlarged sectional detail illustrating the interengagement of the free end of the strap with the tongue on the enclosed end when the tongue on the free end has been flattened into the plane of the strap.

The seal consists of only four principal parts, namely: an elongated strap 14 with parallel sides made of sheet metal having a slight springiness, such as quarter-hard cold rolled steel about .015" thick; a lower sealing shell 15; an upper sealing

2

shell 16; and a slotted disk 18. The strap 14 as is usual, may be embossed with the user's name and a serial number as illustrated in Fig. 1.

Referring to Figs. 3 and 4, the disk 18 is provided with a narrow slot 19 which is slightly wider than strap 14 and disposed centrally of the disk. This disk is secured in position, as shown in Figs. 6, 7 and 8, between the enclosing shells 15 and 16, being seated on the flange 20 of shell 15. Shell 16 has a flange 21 which rests on the disk and the edge of flange 20 is crimped over tightly on the flange 21 to form the bead 22. The lower shell 15 has a slot 24 approximately the same size as the slot 19 in the disk and the parts are assembled with these two slots in alignment.

Referring to Figs. 3 and 4, a portion of the enclosed end of strap 14 is bent approximately at right angles to the body of the strap as shown at 25 and is perforated at 26. Disk 18 is provided with an opening 27 formed by means of a punch and die so as to raise the metal of the disk around the opening to form a tubular rivet 28, as shown in Fig. 3. Rivet 28 passes through opening 26 and is expanded over portion 25 as shown in Fig. 4.

The enclosed end of strap 14 is also provided with an upstanding angularly disposed tongue 29 which is struck up from the metal of the strap, leaving the opening 30.

The free end of the strap, as shown in Figs. 1 and 10, is provided with a slot 31 of sufficient width to freely receive tongue 29. In forming the slot 31, a tongue 32 is also formed and preferably pressed outwardly at an angle to the plane of the strap in a direction such that it will overhang the tongue 29 when the free end of the strap is inserted in the enclosure. The free end of the strap is designated 34.

It will be observed, as shown in Fig. 5, that tongue 29 is disposed at such an angle that it extends upwardly above and across the slot 19 in disk 18. After the strap 14 has been inserted through the element of the lock adapted to receive it, the free end 34 is brought around and inserted through slot 24 in shell 15 and slot 19 in disk 18. As it is pushed through the enclosure provided by the shells 15 and 16, the strap end 34 first engages the under face of the tongue 29, as shown in Fig. 5, and upon further inward movement tongue 29 is sprung back slightly, passing over tongue 32 and, due to its resiliency, snapping into slot 31, as shown in Fig. 6. When tongue 29 snaps into slot 31 it makes an audible click. Due to the fact that the strap passes through the slot 24 in shell 15 it is impossible to

so manipulate the strap as to bend tongue 29 beyond its elastic limit and to so deform it that the seal will not work properly. Upon retraction of the strap, in a downward direction as shown in Fig. 7, tongue 29 engages the underside of tongue 32, preventing disengagement of the strap ends. Upon the application of greater force in a direction tending to pull the free end of the strap out of the enclosure, the seal becomes more securely locked, as shown in Fig. 8, from which it will be seen that the tongue 29 has been flattened against the face of disk 18 forming a bridge across the slot 19 and at the same time the tongue 32 has been bent at right angles to the strap 34 and flattened against the tongue 29. The bending of the tongue 32 also causes the free end 34 to be bent at an angle so as to overlie the free end of the tongue 29. This bending of end 34 occurs because the width of tongue 32 is equal to or greater than the sum of the widths of the legs 36 and 38 on either side of it and therefore the legs bend with the tongue, tipping over the end 34.

It will be noted that the strap 14, including its integral tongues, may be cut from either sheet or strip stock without wasting any metal since no part of the strap is wider than any other.

While the enclosed end of strap 14 has been shown as secured to the disk 18 by means of an integral rivet, this connection may obviously be made in other ways as by using a separate rivet, by spot welding or by bending a portion of the strap around a portion of the disk or through an opening provided therein for that purpose. It is also possible to form the seal without this permanent connection between the enclosed end of the strap and the disk since the interengagement of the ends can be effected in the absence of this connection merely by holding the enclosed end as the free end is pushed past it.

The accidental damage to which the seal is most likely to be subject is that tongue 32 will be flattened into the plane of strap 14. Even if this should happen the seal remains operative because tongue 29 will snap into slot 31 even when tongue 32 is in the plane of the strap, as shown in Fig. 11. Thereafter, as the free end is pulled downwardly, the end of tongue 32 will engage tongue 29 causing tongue 29 to be bent toward the disk with the result that tongue 32 will overlie it and will be bent in the same manner as described above in connection with Figs. 7 and 8.

The invention thus provides a seal of the type described which is positive and sure in its action, not likely to be rendered inoperative by accidental damage and which cannot be opened after once being engaged without leaving obvious signs of tampering.

In view of obvious modifications which may be made in the embodiment herein particularly described without departing from the spirit of the invention, it is to be construed broadly within the purview of the claims.

What is claimed is:

1. A seal comprising a hollow body providing an enclosure, a slotted disk extending across said enclosure and secured therein, said body having a slot aligned with the slot in said disk, a strap having a permanently enclosed end extending through both of said slots and a bent portion overlying said disk and adapted to rest upon the face thereof to prevent withdrawal of said end through the slot in the disk, said end also having a tongue extending upwardly from said bent portion and initially disposed at an angle to said

disk and extending across the slot therein, the other end of said strap having a slot adapted to receive said tongue when said other end is inserted into said enclosure and pushed through the slot in the disk and past said tongue.

2. A seal comprising a hollow body providing an enclosure, a slotted disk extending across said enclosure and secured therein, said body having a slot aligned with the slot in said disk, a strap having a permanently enclosed end extending through both of said slots and fastened to said disk, said end also having a tongue initially disposed at an angle to said disk and extending across the slot therein, the other end of said strap having a slot adapted to receive said tongue when said other end is inserted into said enclosure and pushed through the slot in the disk and past said tongue.

3. In a seal, an enclosure formed by a pair of shells permanently secured together, a slotted disk extending across said enclosure and secured between said shells, one of said shells having a slot aligned with the slot in said disk, a strap having one end which extends through both of said slots, a portion of said end being bent parallel to and adapted to rest upon the face of said disk, said end also having an integral tongue disposed at an angle to said disk and extending across the slot therein, the other end of said strap having a slot adapted to receive said tongue, said other end having a second tongue directed toward said last-mentioned slot, said second tongue being adapted to engage behind said first-mentioned tongue when said other end of said strap is inserted through the slot in the disk.

4. In a seal, an enclosure formed by a pair of flanged shells, a slotted disk extending across said enclosure and secured between the flanges of said shells, the flange of one shell being crimped over the flange on the other shell, one of said shells having a slot aligned with the slot in said disk, a strap having one end which extends through both of said slots, a portion of said end being bent parallel to and adapted to rest upon the face of said disk, said end also having an integral tongue disposed at an angle to said disk and extending across the slot therein, the other end of said strap having a slot adapted to receive said tongue.

5. In a seal, an enclosure formed by a pair of shells permanently secured together, a slotted disk extending across said enclosure and secured between said shells, one of said shells having a slot aligned with the slot in said disk, a strap having one end which extends through both of said slots, a portion of said end extending parallel to and adapted to rest upon the face of said disk, said end also having an integral tongue disposed at an angle to said disk and extending across the slot therein, the other end of said strap having a slot adapted to receive said tongue and a tongue bounded in part by said last-mentioned slot, the last-mentioned tongue projecting from the strap in a direction facing toward the first-mentioned tongue when said other end is inserted in said enclosure.

6. In a seal, an enclosure formed by a pair of shells permanently secured together, a slotted disk extending across said enclosure and secured between said shells, one of said shells having a slot aligned with the slot in said disk, a strap having one end which extends through both of said slots, a portion of said end being bent parallel to the face of said disk, means fastening said portion to said disk, said end also having an in-

tegral tongue disposed at an angle to said disk and extending across the slot therein, the other end of said strap having a slot adapted to receive said tongue when said other end is pushed through said slots.

7. In a seal, an enclosure formed by a pair of shells permanently secured together, a slotted disk extending across said enclosure and secured between said shells, one of said shells having a slot aligned with the slot in said disk, a strap having one end which extends through both of said slots, a portion of said end being bent parallel to the face of said disk, an integral rivet formed from said disk fastening said portion to the disk, said end also having an integral tongue disposed at an angle to said disk and extending across the slot therein, the other end of said strap having a slot adapted to receive said tongue when said other end is pushed through said slots.

8. A seal comprising an enclosure formed by a pair of shells permanently secured together, a slotted disk extending across said enclosure and secured between said shells, one of said shells having a slot aligned with the slot in said disk,

a strap having one end which extends through the slot in the shell and is bent so as to lie parallel to a face of said disk, the bend in the end of the strap being adjacent one edge of the slot in the disk, said strap end being permanently connected to said disk and having an integral tongue initially extending angularly across the slot in the disk, the other end of the strap having a slot adapted to receive said tongue when said other end is pushed through the slot in the disk and past said tongue.
